Inventor:

Margo R. Alexander,
By Shindell U. Parker, Esq.

Atty:

UNITED STATES PATENT OFFICE

MARGO R. ALEXANDER, OF CHICAGO, ILLINOIS

BRASSIÈRE

Application filed October 29, 1930. Serial No. 491,828.

The object of my invention is to provide a brassière embodying improved means for supporting the breasts through the application of upwardly and inwardly directed pressure beneath and at the sides thereof, whereby to improve the contour of the feminine figure.

The object of the invention thus generally stated, together with other and ancillary advantages, is attained by the construction and arrangement illustrated in the accompanying drawings, in which:

Figure 1 is a front view of the improved brassière illustrating its application to the body of the wearer.

Fig. 2 is a rear view of the garment in extended form.

In the embodiment of the invention illustrated, the improved brassière comprises a fabric belt 3, the ends of which are adapted to be fastened together at the front of the body as by means of a button 4 engaging in one of a plurality of buttonholes 5. It is intended that the belt shall fit snugly about the body, and to avoid undue binding it is preferably made in two sections connected at the rear of the body by means of an elastic strap 6.

At opposite ends of the belt are provided two supports generally designated by the numeral 7. These supports are made of cloth or other suitable material, and in the present instance are formed from two substantially triangular pieces 8 and 9 stitched together and to the belt in overlapping relation so as to form an upwardly opening, substantially V-shaped recess.

Each of the supports 7 has connected to opposite sides thereof a suspender strap 10, one end of the suspender strap being preferably permanently secured to the upper end of the triangular piece 8 of the support, and the other end of the strap being adjustably secured to the upper end of the piece 9 as by means of a button 11 engaging in one of a plurality of button holes 12. By this adjustment it is possible readily to vary the lateral pressure exerted by the suspender straps upon the breasts.

Between its ends each of the straps 10 slidably engages with the forward end of a

shoulder strap 13, the rear end of which is connected to the central rear portion of the belt as by being secured to an anchoring piece 14. The slidable connection between the forward end of the shoulder strap 13 and the strap 10 is effected by means of a loop 15 formed in the strap 13, through which loop the strap 10 is inserted.

The parts are so proportioned that with the brassière in place on the body, the belt 3 has a snug fit immediately below the breasts, so that the latter may be received within the V-shaped recesses of the supports. Thus the side edges of the recesses engage beneath and laterally of the breasts, and the shoulder straps 13 acting through the medium of the straps 10 exert an upward and rearward pull on the sides of the recesses with a resulting inward pressure around the lower and side portions of the breasts. Such pressure is equalized on opposite side portions of each support by reason of the sliding connection between the straps 10 and the shoulder straps 13 so as to insure ease and freedom of movement.

It has been found that with the construction thus provided, the breasts are effectively supported from beneath and from the sides thereof, and the contour of the figure is thus substantially improved.

I claim as my invention:

1. A brassière comprising an elongated belt adapted to be fitted snugly around the body of the wearer, a pair of supports carried on the upper edge of the belt at the forward side of the body, said supports having edge portions shaped to engage the lower and side portions of the breasts, and means for exerting upward and lateral pressure on the breasts through the medium of said supports, comprising a pair of suspender straps and shoulder straps having their rear ends connected to the rear portion of the belt and their forward ends adjustably connected to the respective suspender straps intermediate the ends thereof, each of said straps having its opposite ends secured to the opposite sides of its support and one of said ends being removably fastened to the support.

2. A brassiere comprising an elongated

belt adapted to be fitted snugly around the body of the wearer, a pair of supports carried by the belt and having upwardly opening substantially V-shaped recesses to receive the breasts, and means for exerting upward and lateral pressure on the breasts through the medium of said supports, said pressure exerting means comprising a pair of shoulder straps and a pair of supporting straps 5 slidably connected between their ends to the shoulder straps and secured at their ends to said supports at opposite sides of said V-shaped recesses, one end of each of said supporting straps being adapted to be secured 10 to its support with a disengageable connection.

3. A brassière comprising an elongated belt adapted to be fitted snugly about the body of the wearer and having means for 20 fastening its free ends together at the front side of the body, a pair of shoulder straps each having its rear end anchored to the belt rearwardly of the body and approximately centrally thereof, a pair of suspender straps 25 slidably connected between their ends to the forward ends of said shoulder straps at a point forwardly of the body and above the breasts, and a pair of substantially V-shaped supports of flexible material secured to the 30 forward side of the belt and adapted to engage the lower and side portions of the breasts, said suspender straps having their opposite ends fastened to opposite sides of said supports and serving through the medium 35 of the supports to exert an upward and inward pressure on opposite sides of the breasts, and said suspender straps being adjustable to vary the lateral pressure exerted thereby upon the breasts.

4. A brassière comprising a belt adapted 40 to fit snugly about the body of the wearer, a pair of supports carried by the belt forwardly of the body and each comprising two substantially triangularly shaped pieces of cloth 45 or the like secured together in overlapping relation so as to form a substantially V-shaped upwardly opening recess, a strap secured at its opposite ends to said support at opposite sides of said recess, and a shoulder 50 strap anchored to the belt rearwardly of the body and slidably connected to said supporting straps substantially midway between the ends of the latter, said straps being operable to exert an upward and rearward force upon 55 opposite sides of the support.

5. A brassière comprising a lengthwise adjustable belt adapted to fit snugly about the body of the wearer, a pair of breast supports carried by the belt forwardly of the body and 60 shaped to provide substantially V-shaped upwardly opening recesses for receiving the breasts, a strap for each of said supports permanently fastened at one end to the side of the recess adjacent the side of the body and 65 having its other end adjustably connected at

the opposite side of the recess, and a pair of shoulder straps anchored to the belt rearwardly of the body and having their forward ends slidably engaging said supporting straps intermediate their ends.

In testimony whereof, I have hereunto affixed my signature,

MARGO R. ALEXANDER.
